UNITED STATES PATENT OFFICE.

OMAR MILLARD HIGHLEY, OF CONVERSE, INDIANA.

TYPE-WRITER.

1,189,449.

Specification of Letters Patent.

Patented July 4, 1916.

Application filed December 31, 1915. Serial No. 69,685.

To all whom it may concern:

Be it known that I, OMAR MILLARD HIGHLEY, citizen of the United States, residing at Converse, in the county of Miami and State of Indiana, have invented certain new and useful Improvements in Type-Writers, of which the following is a specification.

This invention relates to a typewriter of that class more particularly characterized by the fact that ribbon inking means for the 10 type characters is completely eliminated.

One object of the present invention resides in providing a typewriter wherein the type members move relative to the platen 15 and to the surface to be printed on, so as to produce line writing in this manner, instead of moving the platen and its supporting carriage as is the case in that class of typewriting machines employing a bank of 20 type members.

Another object resides in the construction wherein a rotatable type member carrying a plurality of type characters arranged in one or more concentric rows is provided, and 25 also in arranging means to select, advance and impress any desired type member.

A further object consists in the particular means for moving the platen relative to the type member.

30 Other objects of this invention will appear in the following description, which is to be considered in connection with accompanying drawings, wherein I have illustrated a specific embodiment of the invention, said embodiment being illustrated merely for the purpose of explaining the 35 principles of this invention, and not imparting a limitation thereto.

In the drawings: Figure 1 is a top plan view of a typewriter constructed according to the principles of my invention. Fig. 2 is a front elevation of the typewriter shown in Fig. 1. Fig. 3 is a side elevation of the typewriter shown in Figs. 1 and 2, and with 45 one side of the frame thereof removed so as to display the details of the mechanism. Fig. 4 is a top plan view of the movable type member. Fig. 5 is an elevation of the face of the rotatable type member or disk. 50 Fig. 6 is a view, in perspective, of the reciprocating shoe for moving the type member. Fig. 7 is a detail view, in perspective, of the escapement mechanism.

In detail: The typewriter, as herein shown, comprises the frame 1, having pivotally mounted thereon at 1^a the arms 2^a

carrying the rotatable platen 2, said arms being normally supported by engagement with stops 2^b, said stops limiting the downward movement but not restricting upward movement. At the back of the platen 2 are provided rollers 3 for engagement with the paper to be held by the platen. Smaller rollers 4 are provided on the front part of the platen to hold the paper in position, 60 while underneath the platen 2 is a curved guard 5 serving to protect the platen and paper. One end of the platen 2 carries a ratchet wheel 6 for engagement by a pawl 7; and a knob 8 is provided which may be 65 used to rotate the platen to advance the paper carried thereby for successive line printing. The pawl 7, by dropping in the various notches of the wheel 6 serves to indicate the proper setting of the platen for 70 different lines of printing.

Beneath the platen 2 and extending transversely of the frame 1 are the two parallel guide bars 9. These bars support a carriage 10 slidable therealong and which 80 is connected with one end of a tension strap 11, the other end of which is connected with a tension spring housed within the casing 12 carried by the frame 1.

The carriage 10 is provided with the front 85 and rear uprights 13 and 14 respectively, in which is journaled the horizontally extending shaft 15 spirally splined as shown at 16 and provided with the reduced rear end portion 17, pointed at its extremity, and 90 bearing on the free end of a U-shaped spring 18, the latter being fastened to the said carriage 10. The forward end of said shaft 15 carries a type member 19 which is fixed thereto so as to be rotatable with the shaft, 95 said type members being preferably in the form of a disk having the individual arms 20 carrying the concentric rows of type and so spaced apart as to render the writing produced visible. The shaft 15 is confined 100 between the uprights 13 and 14 in such a manner that its movement is limited to the length of the extension 17, the forward end of the shaft being extended through said type disk and bearing against a spring 30' 105 carried by the impression lever 30. However, such movement of the shaft is merely to compensate for the impression on the platen of a type character and, strictly speaking the greatest movement that the shaft 15 is 110 capable of is merely to compensate for a blow on the rotatable type member which

blow is absorbed by the spring 18. The type member 19 is provided with a plurality of resilient type arms 20, each of which as hereinbefore stated, carries two type members, the said type members or characters being arranged in concentric rows. Beneath the shaft 15, and slidably along longitudinally of the carriage 10, is a block 21 which seats at 22 on said carriage 10 and the upper face thereof is hollowed out as at 23 to receive the shaft 15, said block, in the hollowed out face, carries a pin 24 for engagement with the spiral spline in said shaft. Thus, as the block 21 is moved longitudinally of the carriage 10, it imparts a rotative movement to the type member or disk 19 through the medium of the shaft 15. Confined between the block 21 and the upright 13 is a spiral spring 25 which acts to always return block 21 to a normal starting position thus after each movement of the type member 19, the same returns to its initial starting position. The type characters are suitably inked by means of an ink supply roller 26 carried by pivot 27 located on the upright 13 of the carriage 10, and as the type disk 19 is rotated this roller 26 rolls successively into engagement with each type character. The carriage 10 carries a depending arm 28 having pivoted thereto at 29 a substantially vertical impression lever 30, the lower end of which is curved around as shown at 31' and connects with a lever 32' which, in turn connects with a bell crank 33' carried by the upright 14 and one arm of which engages with the spring 18, the resiliency of which serves to return said impression lever 30 to its normal position after an impression has been effected. At its upper end the impression lever 30 is provided with a pad 31, for purposes to be hereinafter described. The guide bars 9, along which the carriage 10 moves, are carried by the frame members 1. Engaging with the impression lever and extending across the front of the machine is a bar 36 which is connected at each end with rods 37, the other ends of which connect with the long arm of a bell crank lever 38, the short arm of which is adapted to be engaged by the rear end of a type lever 39, said type lever being pivoted on a shaft 40 and carrying the key 41, thus, as the key 41 is depressed, the bar 36 will move the impression lever 30 into contact with the proper arm 20 opposite the said impression lever and thereby engage the type character on the face thereof with the platen in such a manner as to form an impression. However such impression lever, by means of the resiliency of the spring 18 will be returned to its normal position.

In order to provide for selecting any type character, a bell crank lever 42 is arranged at the rear of the typewriter and is adapted

to have its short arm engaged by a lug 43 carried by the type lever, and the long arm of said bell crank lever 42 is connected by means of rods 44 with a transversely extending bar 45 which engages block 21, and upon depressing the key 41, the said block 21 is moved and which, by reason of the engagement of the pin carried thereby with the spiral spline, rotates the type member 19. The proportionment of said lever hereinbefore described is so arranged that the proper arm 20 carrying the type character indicated on the key 41 will be advanced into printing position.

As before stated, the type member 19 carries a plurality of concentric rows of type characters and, in order to use either row, means for shifting the carriage vertically together with its platen 2 must be provided. Such means consists of the arms 45 which engage with the arms 2a and which, at their other ends are provided with shift keys 46 so marked. Thus as either shift key 46 is depressed the platen 2 will be elevated so that the outer row of type characters may be used for printing purposes. Of course, for advancing the type characters to be in position to be engaged by the impression lever, it is necessary to regulate the rotative travel of the type disk 19. For effecting this the rear end of each type bar is suitably proportioned as shown in Fig. 3.

After each impression it is necessary to space, and the spacing mechanism includes the transversely extending bar 47 provided with teeth 48 said teeth being spaced apart sufficiently to separate the letters when printing. Engaging with said teeth is the pivoted escapement lever 49 carried by the extension 50 of the impression lever and capable of free deflection in one direction, or in other words acting as the pawl of a ratchet. Also carried by the member 50' is the escapement stop 50', thus as the impression lever is rocked the proper spacing will be effected. In order to space without printing the bar 47 is supported on the ends of bell crank levers 51 pivoted at 52 to a shaft mounted in the frame 1, and the other end of each bell crank lever carries the space bar 33, thus when the space bar 33 is moved the type member 19 will be spaced relative to the platen in a longitudinal direction, and by reason of the formation of the escapement, that is to say the spring 49, the type member may be moved back in the usual manner.

The operation of the typewriter is as follows: When it is desired to produce writing, the paper is rolled beneath the platen and extends upwardly as is the case in the usual typewriter. The carriage 10 is then adjusted to the proper position to print a line, and the letters are depressed in succession in the usual manner, but instead of the

platen moving, as is the case in the usual typewriter, the type is moved along relative to the platen and thereby produces a line of writing. After the type member has 5 reached its limit of travel the same is returned to its normal writing position. The machine is then ready to print another line but the paper must be properly spaced by turning the platen knob 8.

10 With this typewriter the key board may be arranged in the usual well known manner, and thus an operator will experience no difficulty in using the same.

15 In the foregoing specification I have described and illustrated one specific embodiment of the invention, but it is to be distinctly understood that modifications may be resorted to without departing from the spirit and scope of the invention as defined 20 in the appended claims.

I claim:

1. A typewriter, including a platen, a rotatable disk having a plurality of resilient radially extending type carrying arms arranged thereupon movable longitudinally of said platen to produce line writing, a spiral shaft for supporting this disk, a slidable block engageable with the spiral shaft for selecting and bringing the particular arm 30 into writing position, means for actuating said slidable block, means for impressing the selected arm, a plurality of levers for successively operating said block actuating means and said impressing means, and resilient means engageable with the slidable block for returning the same to its initial starting position.

2. A typewriter, including a platen, a rotatable disk having a plurality of resilient radially extending type carrying arms movable longitudinally of said platen to produce line writing, a spiral shaft for supporting said disk, a slidable block engageable with the spiral shaft for selecting and bringing 45 the particular arm into writing position, pivotally supported means arranged adjacent the rotatable disk for impressing the selected arm, means for actuating said slid- 50 able block, a plurality of levers for successively operating said block actuating means and said impressing means, and resilient means engageable with said slidable block for returning the same to its initial starting position.

55 3. A typewriter, including a platen, a rotatable disk having a plurality of radially extending type carrying arms movable longitudinally of said platen to produce line writing, a spiral shaft for supporting said 60 disk, a slidable block engageable with the spiral shaft for selecting and bringing a particular arm into writing position, means for actuating said slidable block, a pivotally

supported arm arranged adjacent the disk for impressing the selected arm, resilient means connected with said pivotal arm for returning the same to its normal position, means for actuating said pivotal arm, a plurality of levers for successively operating said block actuating means and said pivotal arm impressing means, and resilient means engageable with said slidable block for returning the same to its initial starting position.

4. A typewriter, including a platen, a rotatable disk having a plurality of resilient radially extending type carrying arms movable longitudinally of said platen to produce line writing, a spiral shaft for supporting said disk, a slidable block engageable with the spiral shaft for selecting and bringing a particular arm into writing position, means for actuating said slidable block, a pivotally supported arm arranged adjacent the disk for impressing the selected arm, 85 means engageable with said pivotal arm for actuating the same, resilient means connected with end of the pivotal arm for returning the same to its normal position, bell crank levers connected with the block actuating means and the pivotal arm impressing means, and a plurality of levers for successively engaging said bell crank arms for moving said block actuating means and pivotal arm impressing means, and resilient 90 means engageable with the slidable block for returning the same to its initial starting position.

5. A typewriter, including a platen, a rotatable disk having a plurality of resilient radially extending type carrying arms movable longitudinally of said platen, to produce line writing, a spiral shaft for supporting said disk, a slidable block engageable with the spiral shaft for selecting and bringing a particular arm into writing position, means for actuating said slidable block, a pivotal arm arranged adjacent the disk for impressing the selected arm, means for actuating said pivotal arm, resilient 100 means for returning said arm to its normal position, spacing means connected with the pivotal arm, bell crank levers connected to the slidable block actuating means and the pivotal impressing arm actuating means, 105 a plurality of levers for successively engaging said bell crank levers whereby to operate said slidable block actuating means and said pivotal impressing arm actuating means, and resilient means engageable with the slidable block for returning the same to its initial starting position.

In testimony whereof I affix my signature.

OMAR MILLARD HIGHLEY.
